Primary Examiner—Sandra Snapp

(74) *Attorney, Agent, or Firm*—Steven B. Stein, Esq.

(57) **CLAIM**

The ornamental design for a child car seat, as shown.

DESCRIPTION

FIG. 1. a front perspective view of a child car seat showing my new design;

FIG. 2. a rear elevation view of the child car seat;

FIG. 3. a side elevation view of the child car seat; and,

FIG. 4. a top plan view of the child car seat.

The broken lines shown in the drawings are for illustrative purposes only and form no part of the claimed design.
